MECHANICAL MOVEMENT

Louis A. Hummel, Waterbury, Conn., assignor to
 The United States Time Corporation, Water-
 bury, Conn., a corporation of Connecticut

Application December 14, 1946, Serial No. 716,284

3 Claims. (Cl. 58—22)

1

This invention relates in general to a means for performing some mechanical operation once during one complete revolution of a member such as a gear or wheel. Specifically, it contemplates the provision of two members which are to be rotated relative to each other and a condition where it is desired that some operation be performed only when the two members are in one relative angular position.

This invention is particularly applicable to timers for measuring elapsed period of time, as well as timepieces in general which continuously measure time and especially timepieces having alarms. In timers, the means comprising the present invention can be used to either control the operation of an audible alarm or the functioning of mechanical or electrical devices at a predetermined time.

The particular embodiment of the invention chosen for illustration is an alarm clock wherein it is desired that the alarm be sounded only once during a complete revolution of the hour hand.

In an alarm clock, it is necessary to provide some means operated by the time train for controlling the sounding of the alarm. It has been the common practice to provide a notch in the hub of the hour wheel and to provide a pin so located that when the hour wheel has moved to a rotary position wherein the notch is in alignment with the pin, the hour wheel may be moved axially so that the pin will be positioned within the lower part of the notch. Some means, such as a long resilient arm, is generally provided to constantly urge the hour wheel towards the aforementioned pin. One end of the resilient arm is generally anchored to one of the frame plates of the clock, and the other end is held in such position during the time that the pin and notch are not in alignment that it will engage the alarm verge or some wheel of the alarm train to prevent the alarm from operating at such time. When the notch moves into alignment with the pin, the resilient arm urges the hour wheel axially and the free end of the arm moves away from whatever part of the alarm train with which it had been engaged to thereby allow the alarm to be sounded. Since it is desirable that the alarm be sounded only once during one complete twelve-hour revolution of the hour hand, which is attached to the hour wheel, only one pin and one notch can be provided. Therefore, a line contact is established between the pin and the hub of the hour wheel whereby that part of the hub which is in contact with the pin cannot move axially but that part of the hub which is diamet-

2

rically opposite the pin will be moved axially by the resilient arm. Such an arrangement results in a tendency for the hour wheel to be cocked or skewed and such cocking or skewing causes an undue amount of wear and is apt to result in an unstable movement of the hour wheel.

It is a broad object of this invention to provide an improved arrangement whereby some mechanical operation will be performed when two relatively rotatable members arrive at a predetermined relative angular position.

It is a specific object of this invention to provide an inexpensive means operable by the time train of a clock for controlling the sounding of an alarm, which means will not cause cocking of any of the wheels of the clock.

It is a further object of this invention to provide, in an alarm clock having co-axially mounted time and alarm indicating hands, a means for controlling the let-off or sounding of the alarm which will not result in any axial movement of any of the wheels of the time train or the alarm train or the dial train.

It is a still further object of this invention to provide a means for controlling the let-off or sounding of the alarm of a clock which will not result in a cocking or skewing of any of the vital parts of the clock, nor, more particularly, of any part of the control mechanism per se.

These and further objects of the invention will more readily appear as the description of one specific embodiment of the invention proceeds. Referring now to the drawings wherein:

Fig. 1 is an exploded view partially in section of the alarm control means of this invention.

Fig. 2 is an assembled sectional view of the alarm control means showing the parts in the position which they assume during the sounding of the alarm.

Fig. 3 is a side elevational view, partially in section, of the alarm control means with certain of the parts being shown in full lines as they appear during the period when the alarm is not being sounded and being shown in dotted lines in the position which they assume during the sounding of the alarm.

Fig. 4 is a view of certain of the elements seen from the line 4—4 of Fig. 3.

Fig. 5 is a perspective view of one of the elements of the alarm control means.

Fig. 6 is a view of certain of the elements seen from the line 6—6 of Fig. 1.

Referring now to Fig. 1 of the drawings wherein the vital parts of the invention are shown in unassembled condition; the front frame plate

of the clock is indicated at 2 and the center arbor is shown at 4 with the pinion 6 fixed thereto. A post 8 is shown fixed in the frame plate 2 and the idle wheel 10 having an integral pinion 12 is rotatably mounted upon the post 8. At 14 is shown a long resilient arm having an opening 16 near the center thereof. This resilient means or arm 14 is fixed to the frame plate 2 at one end thereof by means of a screw 18. When one end of the arm 14 is attached to the frame plate 2, the opening 16 freely accommodates the center arbor 4 and the resiliency of the arm is such as to cause the free end and the intermediate portion thereof to be urged in an upward direction as seen in Figs. 2 and 3.

Fig. 5 shows in perspective one of the important elements of this invention. Said element is indicated by reference character 20 and is a small light weight member carrying cams 22 and 24. The high points of the cams are indicated at 26 and 28 respectively, and as seen in Fig. 4, these high points 26 and 28 are diametrically opposed. The element 20 also carries a pair of diametrically opposed lugs 30 and 32 which terminate in flat ends, the leading edges of which in the direction of their movement, to be described, are preferably beveled as indicated at 34 and 36 respectively for a purpose also to be presently described. It will be noted from Fig. 4 that the lugs 30 and 32 are diametrically opposed and are spaced approximately mid-way between the high points 26 and 28 of the cams 22 and 24. Obviously the cams 22 and 24 could be slightly displaced from a diameter if desired, as could also the lugs 30 and 32.

The hour wheel of the clock is indicated at 38 and said hour wheel is provided with a longitudinally extending hub 40, one end of which is indicated at 42 and the other at 44. The hour wheel is made fast with the hub by staking or swaging or in any other desired manner. If desired, the hour wheel 38 and the hub 40 may be formed integrally by molding or by cutting the two members from a single piece of stock.

The hour wheel 38, and it will be understood that insofar as the broad aspects of this invention are concerned the wheel 38 may be any driven member, is provided with a pair of openings 46 and 48 for accommodating the cams 22 and 24 respectively. As seen in Fig. 4, the hour wheel 38 is also provided with a pair of openings 50 and 52 for accommodating the lugs 30 and 32 respectively. It will be noted from Fig. 4 that the cam receiving openings 46 and 48 are spaced at equal radial distances from the center of the hour wheel 38 and that the openings 50 and 52 are spaced at different radial distances from the center of the hour wheel, in order that they may accommodate the lugs 30 and 32 respectively which are spaced at different radial distances from the center of element 20. It will further be noted that the opening 50 is radially nearer the center of wheel 38 than are the openings 46 and 48 and that the opening 52 is located at a greater radial distance from the center of wheel 38 than are the openings 46 and 48.

In assembling the parts thus far described, the element 20 is placed upon one end 42 of the longitudinally extending hub 40 and the cams and lugs carried by the element 20 are received within the openings provided therefor in the hour wheel. The hub 40 is then placed over the center arbor 4 in such manner that the end 42 of the hub 40 extends through the opening 16 in the arm 14.

The alarm set wheel is indicated at 54 and it is provided with a hub 56 having a flange 58 on one end thereof, said flange being considered a part of said wheel. The alarm set wheel 54 is fastened to the hub 56 by staking or by some other suitable means in such manner that the flange 58 bears against one side of the set wheel. Here again, it will readily be appreciated that the set wheel 54 and the hub 56 may be integrally formed. The set wheel 54 may be rotated relative to the hour wheel 38 by means of a pinion 60 fastened to a staff 62. The staff 62 is provided with a manually operable knob, not shown, protruding from the back of the clock.

As best seen in Fig. 2, the flange 58 is provided with a pair of lug receiving openings 64 and 66 for receiving the lugs 30 and 32 respectively. The flange 58 is likewise provided with a pair of cam receiving openings 65 and 67, as seen in Fig. 6.

The next step in assembling the clock consists of mounting the hub 56 of the set wheel 54 upon the hub 40 of the hour wheel 38. The various parts thus far described are then held in position by means of a bridge 68, the bridge being fastened to the frame plate 2 by means of a pair of ears 70 and 72.

Describing now the operation of the parts thus far referred to, it will be understood that the center arbor 4 is driven by the main wheel of the clock and carries upon its outer end the minute hand of the clock. The hour wheel 38 is driven from the pinion 6 through the idle wheel 10 and pinion 12 and carries upon the outer end of the hub 40 the hour hand of the clock. The outer end of hub 56 carries the alarm indicating hand. The free end 74 of the resilient arm 14 is normally engaged with a portion 76 of the alarm verge and prevents said verge from moving.

The alarm set wheel 54 may be turned by the pinion 60 to any desired rotary position at which it remains stationary relative to the clock movement until moved to a different setting. As the hour wheel 38 rotates, it will carry with it the element 20, since as previously pointed out the cams 22 and 24 and the lugs 30 and 32 thereon extend through openings provided therefor in the hour wheel and the two therefore rotate as a unit relative to the alarm set wheel while being capable of relative axial movement. The ends of all of said cams and lugs lie in a common plane and said ends normally slide on one surface of the alarm set wheel, specifically, the hub 58 thereof. At one relative angular position between the hour wheel and the set wheel however, the openings in the hour wheel will come into longitudinal alignment with the openings in the set wheel and at that time the resilient arm 14 will move the element 20 from the position shown in Fig. 3 to the position shown in Fig. 2 wherein the cams and lugs are received within the openings provided therefor in the set wheel. From an inspection of Fig. 6, it will readily be seen that the lugs 30 and 32 can be moved into the openings 64 and 66 respectively of the flange 58 of the set wheel only when the lugs 30 and 32 are in one particular angular position with respect to the openings 64 and 66. This is true because of the fact that the openings 50 and 52 of the hour wheel 38 and the corresponding openings 64 and 66 of the set wheel are placed at different radial distances. In other words, the lug 30 can never be received by the opening 66 because when the lug 30 is in angular alignment with the opening 66, it will not be in longitudinal alignment (radial coincidence) therewith but will

be radially nearer the center of rotation than the opening 66. Likewise, the lug 32 can never be engaged within the opening 64 because when the lug 32 and the opening 64 are in angular alignment, they will not be in longitudinal alignment. 5

After the cams and lugs of the element 20 have been received within the openings provided therefor in the flange 58, the free end 74 of the resilient arm 14 will move away from the portion 10 76 of the alarm verge and thereby allow the verge to be moved by the alarm train of the clock; since as previously pointed out, the arm 14 is such that its inherent resiliency will cause the free end 74 and the intermediate portion of the arm to move upward as seen in Fig. 3.

After the alarm has been sounded and the hour wheel continues to move, the cams 22 and 24 will cause the element 20 to be pushed downward as seen in Figs. 2 and 3 until the high points 26 and 20 28 are engaged with the flat surface of the flange 58 adjacent the edges of the openings. Since the element 20 will have a tendency to tilt about the points 26 and 28, the lugs 30 and 32 have been provided with tapered edges 34 and 36 to reduce 25 possible wear and drag on the alarm set wheel and also for the purpose of engaging the edge of one or the other of the openings 64 and 66 to insure that the lugs 30 and 32 will be moved out of their respective openings in the alarm set wheel. At this time, the element 20 is supported by the ends of the cams 22 and 24 and lugs 30 and 32 which slide upon the smooth surface of the flange 58 between the openings therein so that there will be no tendency for the element 20 to cock or skew relative to said wheel, as would be the case were only two points of support for the element 20 provided. The cams 22 and 24 serve as a means for moving the element 20 towards the resilient arm 14 and the lugs 30 and 32 serve as an additional means for holding the element 20 against the resilient arm 14 and for leveling element 20 relative to the hour wheel and set wheel. It will readily be seen that the same effect could be obtained by locating the lugs 30 and 32 at the same radial distance while placing the cams 22 and 24 at different radial distances. However, it is preferred to have the cams spaced equal radial distances and the lugs different radial distances since even pressure is thus placed on said cams during the time they are being cammed out of the openings 65 and 67 in the alarm set wheel.

While the invention has been shown as embodied within an alarm clock, it will readily be appreciated that in essence the hour wheel 38 merely serves to represent any rotatably mounted member and likewise the alarm set wheel 54 is merely representative of a second member rotatable relative to the first member. Likewise, while the free end 74 of the resilient arm 14 has been shown as engaging part of an alarm verge, it will readily be appreciated that the free end 74 is actually a control device and may serve to operate an electrical contact or to open a valve or perform most any mechanical function.

While the invention has been illustrated and described in its preferred embodiments and has included certain details, it should be understood that the invention is not to be limited to the precise details herein illustrated and described since the same may be carried out in other ways, falling within the scope of the invention as claimed.

What I claim is:

1. In a timing instrument having an alarm, a control member and actuating means for said control member comprising a driven wheel, a pair of openings in said wheel, a member concentric with said wheel and having a pair of cams so constructed and arranged that they extend respectively through said openings in said wheel, said member being movable axially relative to said driven wheel to control the operation of said alarm, and an alarm set wheel mounted in co-axial relation to said driven wheel and rotatable but not axially movable relative thereto, said alarm set wheel having cam-receiving openings corresponding in number and radial position to the openings in said driven wheel and registrable therewith in one relative angular position of said wheels; in combination with a pair of lugs carried by said member and terminating in flat ends, and the driven wheel and alarm set wheel also being provided respectively with pairs of openings to receive said lugs, the ends of said lugs and cams being disposed in a common plane parallel to one surface of said alarm set wheel and either the pair of lugs or pair of cams and the respective openings in the wheels to receive the same being unequally spaced radially from the axis of said wheels and the other pair and the openings therefor being equally spaced radially from said axis but a distance different from either of said unequal radial distances, whereby the lugs and cams will normally slide on said surface of said alarm set wheel and due to said unequal radial distances will register with their respective cam and lug-receiving openings in the wheels at only one relative angular position of said wheels to permit movement of said member toward said alarm set wheel and actuate said control member in one direction, said 40 lugs and cams cooperating to prevent said member from tilting relative to said wheels and said lugs also serving to reduce wear on said cams during movement relative to said alarm set wheel.

2. In a timing instrument having an alarm, 45 a control member and actuating means for said control member comprising a driven wheel, a pair of openings in said wheel, a member concentric with said wheel and having a pair of diametrically opposed cams so constructed and arranged that they are radially equidistant from the axis of said member and extend respectively through said openings in said wheel, said member being movable axially relative to said driven wheel to control the operation of said alarm, and 50 an alarm set wheel mounted in co-axial relation to said driven wheel and rotatable but not axially movable relative thereto, said alarm set wheel having cam-receiving openings corresponding in number and radial position to the openings in 55 said driven wheel and registrable therewith in one relative angular position of said wheels; in combination with a pair of lugs carried by said member and terminating in flat ends, and the driven wheel and alarm set wheel also being 60 provided respectively with pairs of openings to receive said lugs, the ends of said lugs and cams being disposed in a common plane parallel to one surface of said alarm set wheel and the pair of lugs and the respective openings in the wheels 65 to receive the same being unequally spaced radially from the axis of said wheels which distances are different from the equal radial distances of said cams, whereby the lugs and cams will normally slide on said surface of said alarm set 70 wheel and due to said unequal radial distances 75

7
of said lugs will register with their respective cam and lug-receiving openings in the wheels at only one relative angular position of said wheels to permit movement of said member toward said alarm set wheel and actuate said control member in one direction, said lugs and cams cooperating to prevent said member from tilting relative to said wheels and said lugs also serving to reduce wear on said cams during movement relative to said alarm set wheel.

3. In a timing instrument having an alarm, a control member and actuating means for said control member comprising a driven wheel, a pair of openings in said wheel, a member concentrically rotatable with said wheel and having a pair of cams so constructed and arranged that they extend respectively through said openings in said wheel, said member being movable axially relative to said driven wheel to control the operation of said alarm, and an alarm set wheel mounted in co-axial relation to said driven wheel and rotatable but not axially movable relative thereto so as to be settable in various predetermined positions, said alarm set wheel having cam-receiving openings corresponding in number and radial position to the openings in said driven wheel and registrable therewith in one relative angular position of said wheels; in combination with a pair of lugs carried by said member and terminating in flat ends the leading edges of which are beveled, and the driven wheel and alarm set wheel also being provided respectively with pairs of openings to receive said lugs, the ends of said lugs and cams being disposed in a common plane parallel to one surface of said alarm set wheel and either the pair of lugs or pair of cams and the respective openings

8
in the wheels to receive the same being unequally spaced radially from the axis of said wheels and the other pair and the openings therefor being equally spaced radially from said axis but a distance different from either of said unequal radial distances, whereby the lugs and cams will normally slide on said surface of said alarm set wheel and due to said unequal radial distances will register with their respective cam and lug-receiving openings in said wheels at only one relative angular position of said wheels to permit movement of said member toward said alarm set wheel and actuate said control member in one direction, said lugs and cams cooperating to prevent said member from tilting relative to said wheels and said lugs also serving to reduce wear on said cams during movement relative to said alarm set wheel whereas the beveled leading edges of the ends of said lugs serve to reduce wear on the alarm set wheel.
